RELAY

Norman F. Agnew, Swissvale, Pa., assignor to The Union Switch & Signal Company, Swissvale, Pa., a corporation of Pennsylvania

Application September 7, 1934, Serial No. 743,867

2 Claims. (Cl. 260—122)

My invention relates to relays and particularly to relays of the type having a conducting liquid for making and breaking circuits.

I will describe several forms of relays embodying my invention, and will then point out the novel features thereof in claims.

In the accompanying drawing, Figs. 1 and 2 are diagrammatic views of two forms of relays each embodying my invention. Fig. 3 is a diagrammatic view of a modification of a portion of the relay shown in Fig. 1, and also embodying my invention. Fig. 4 is a plan view of a modified form of relay also embodying my invention, and Fig. 5 is a sectional view of Fig. 4 along the line 5—5.

Similar reference characters refer to similar parts in each of the views.

Referring first to Fig. 1, the reference character 1 designates a non-conducting container made, for example, of glass and consisting of two chambers connected together at the lower end by a tube. The upper portion of each chamber contains an inert gas 6, such, for example, as hydrogen. The lower portion of each chamber and the tube contain a conducting liquid 2, preferably mercury, with the liquid free to flow between the chambers. When the conducting liquid 2 is at the normal level, as herein shown, a contact 7 is immersed in the liquid and a contact 11 is above the level of the liquid. A contact 9 is immersed in the liquid at all times regardless of changes in the level of the liquid. This arrangement of contacts is similar to the contacts in the usual type of relay wherein contact 9 is the heel, contact 7 is the back contact and contact 11 is the front contact. The chamber at the left of the drawing contains also, a heating element 5, connected to a terminal 3, and a terminal 4, which are analogous to the operating winding and terminals of the usual type of relay.

To operate the relay a source of current is applied to terminals 3 and 4 of heating element 5. The heat generated by the element 5 expands the volume of gas 6. The resulting increase in gas pressure lowers the liquid level in the left-hand chamber below contact 7 and raises the level of the liquid in the right-hand chamber above contact 11. The level of the liquid then remains stationary as long as the current is applied to the heating element. When the current is removed from the heating element, the gas in the left-hand chamber cools and contracts with a resulting decrease in pressure which allows the liquid to return to the normal level.

It is apparent from the foregoing description

that a circuit can be made or broken in response to the energization or deenergization of heating element 5 by the resulting immersion or non-immersion of either contact 7 or contact 11 in the conducting liquid.

Referring now to Fig. 2, the relay here shown contains a conducting liquid 2, and an inert gas 6, and is constructed similar to the relay shown in Fig. 1, except that the container 1 is balanced on a fulcrum 8, and the right-hand chamber is provided with a heating element 5*, connected to a terminal 3* and a terminal 4*, similar to the heating element 5 and terminals 3 and 4 in the left-hand chamber. Thus the container is free to assume an inclined position in response to the distribution of the liquid and can be tilted from side to side depending upon which heating element is energized. Continuous energization is not required because the container is held by gravity in the position to which it was last operated. The contacts 7, 9 and 11 are similar to the contacts having the same reference characters in Fig. 1, and contacts 7 and 11 are immersed or not in the liquid depending upon to which side the container is tilted.

Referring now to Fig. 3, the modified portion of the relay here shown is similar to the left-hand chamber of the relay shown in Fig. 1, with the addition of a resistor 13, in series with the heating element 5. Under normal conditions, as shown herein, the resistor 13 is immersed in the liquid 2. It is therefore shunted and is not effected for limiting the flow of current in the heating element 5. This arrangement provides a circuit of a relatively low resistance which permits a higher temperature for heating element 5 and therefore a quicker change in the level of the liquid. After the liquid in the left-hand chamber is forced downward to a predetermined level in response to the energization of heating element 5, the resistor 13 is free of the liquid and is therefore effective for limiting the flow of current in the heating element 5, thus saving energy during the remaining portion of the energized period.

The resistor 13 is shown in the horizontal position which causes a sudden change in the resistance of the heating element circuit because the entire resistor is free from the shunt imposed by the liquid at the moment the level of the liquid falls below the level of the resistor. If it is desired to produce a gradual change in the resistance of the heating element circuit, the resistor 13 can be placed in a vertical or in an inclined position so that the fall of the level of the mercury uncovers the resistor gradually.

While the resistor 13 shown in Fig. 3 is described as a feature applicable to the relay shown in Fig. 1, it can also be applied to the relay shown in Fig. 2.

5 Referring now to Figs. 4 and 5, I have here shown an assembly, in a case 10, of four individual relays, but I will describe only one relay since all are identical in structure and operation. A non-conducting tube 1^a, open at each end and 10 containing a conducting liquid 2, is enclosed in a case 10 which is divided into two chambers by a baffle plate 12, each chamber containing an inert gas 6. When the conducting liquid 2 is at the normal level, as herein shown, a contact 7^a is 15 immersed in the liquid and a contact 11^a is above the level of the liquid. A contact 9^a is immersed in the liquid at all times regardless of the level of the liquid. The left-hand chamber is provided with a heating element 5^b to which is 20 connected a terminal 3^b and a terminal 4^b. To operate the relay a source of current is applied to the heating element 5^b through terminals 3^b and 4^b. The heat generated by the element 5^b expands the inert gas 6. The resulting increase 25 in gas pressure lowers the level of the liquid in the left-hand side of the tube below contact 7^a and raises the level of the liquid in the right-hand side of the tube above contact 11^a, thus providing a means for making or breaking a circuit similar 30 to that described for the relay shown in Fig. 1.

The tubes designated by the reference characters 1^b, 1^c and 1^d with associated contacts 7, 9 and 11 having the same exponents, correspond in all respects to the tube 1^a with its associated 35 contacts 7^a, 9^a and 11^a. Each tube with its associated contacts is insulated from the other tubes and associated contacts in order that the circuits controlled by the relay can be kept separate.

Since the gas chamber and the heating element are common to all tubes, it is readily apparent that the pressure on the liquid is uniform and therefore a number of circuits can be made or broken simultaneously in response to energization or deenergization of the heating element. 40

45 The relay shown in Fig. 2 can also be used for an assembly similar to that shown in Figs. 4 and 5.

Although the relay shown in Figs. 4 and 5 consists of an assembly of four individual tubes with associated contacts, this relay can consist of any convenient number of tubes and associated contacts.

It is understood that container 1, or tube 1^a, need not necessarily be made of glass, that liquid conductor 2 need not necessarily be mercury and that inert gas 6 need not necessarily be hydrogen, as any materials or substances having similar and suitable characteristics can be used. 5

From the foregoing description it is apparent that my invention has certain advantages over the usual type of relay. It has no moving contacts and requires no magnetic structure or coils. 10 It is universal for either alternating or direct current operation. It can handle heavy loads since circuits are made or broken in the presence of an inert gas. The contacts are of low resistance and are permanent since no contact spring pressure is involved. A number of contacts may be made or broken simultaneously 15 since the gas pressure on the liquid in each tube is equal, and a wide range of time elements can be obtained by varying the current supplied to the heating element or by other means well known to those skilled in the art.

Although I have herein shown and described only a few types of relays embodying my invention, it is understood that various changes and modifications may be made therein within the scope of the appended claims without departing from the spirit and scope of my invention. 25

Having thus described my invention, what I 30 claim is:

1. A relay, comprising a non-conducting chamber containing a conducting liquid and an inert gas, a contact immersed or not in the liquid when the level of said liquid changes in response to 35 a change in the volume of said gas, a heating element for governing the volume of said gas, a resistor contained in said chamber and immersed or not in said liquid according to the level of the liquid, and a circuit for said heating element including said resistor. 40

2. A relay, comprising a plurality of non-conducting tubes of equal size each containing an equal amount of a liquid conductor, a non-conducting chamber containing an inert gas and enclosing said tubes, a plurality of uniform contacts simultaneously immersed or not in the liquid according to the uniform level of said liquid, and a heating element for controlling the volume of said gas to govern the uniform level of said 45 50 liquid.

NORMAN F. AGNEW.
